UNITED STATES PATENT OFFICE.

EUGENE B. HARRINGTON, OF JAMESTOWN, NEW YORK, ASSIGNOR OF ONE-HALF TO
C. FRED DANIELSON, OF JAMESTOWN, NEW YORK.

STRINGED MUSICAL INSTRUMENT.

1,392,053.

Specification of Letters Patent. Patented Sept. 27, 1921.

Application filed November 15, 1920. Serial No. 424,162.

To all whom it may concern:

Be it known that I, EUGENE B. HARRINGTON, a citizen of the United States, residing at the city of Jamestown, in the county of 5 Chautauqua and State of New York, have invented certain new and useful Improvements in Stringed Musical Instruments, of which the following, taken in connection with the accompanying drawings, is a specification.

The invention relates to stringed musical instruments; and the object of the improvement is to provide, first, an arrangement of strings whereby the singing effect of the steel 15 guitar is joined with other accompaniment strings so attuned as to obtain the effect of a lead or melody instrument accompanied by one or more guitars or stringed instruments, and toward this end the strings for the 20 said lead or melody instrument are placed alongside a group of accompaniment strings tuned to the same key so that the steel used in playing may extend over said group of accompaniment strings and so that one stroke 25 of the pick will strike both sets of strings; and second, a further improvement consists in providing an arm or pedal actuation for rotatable fret or pitch bars by which the pitch of said accompaniment strings may be raised 30 or lowered as desired in order to provide the desired accompaniment for the guitar strings, the provision being made for a plurality of said rotatable fret bars and the manipulation thereof; and third, to provide 35 a sound box having sound openings in the sides and back of the same rather than in the sound board so as to obtain increased resonating power for the sound board; and the invention consists in the novel features 40 and combinations hereinafter set forth and claimed.

In the drawings, Figure 1 is a perspective view of the improved harp in table form with pedal actuation for the rotatable pitch 45 or fret bars. Fig. 2 is an inverted perspective view of the preferred form of sound box with the back removed therefrom showing the bridging bar construction in the lower end of the same to support the sound board against the heavy draw of the strings. Fig. 3 is a crosswise sectional view of said sound box on line 3—3 of Fig. 4, and Fig. 4 is a lengthwise sectional view of the sound 50 box on line 4—4 of Fig. 1 showing the preferred arrangement of the same. Fig. 5 is

a perspective view of the harp. Fig. 6 is an edgewise elevation showing said connection to said rotatable pitch or fret bars in normal position; Fig. 7 shows one of said pitch or fret bars actuated by the partial downward pressure on the hinged arm board; Fig. 8 shows the complete depression of said arm board and the actuation of both of said rotatable pitch or fret bars; and Fig. 9 is a sectional view of said arm board and the angular bracket support therefor at the end.

Like characters of reference refer to corresponding parts in the several views.

The numeral 10 designates the sound box which has the sound board 11 extending over 70 the top, the back 12, the front side 13 and the rear side 14, and the pin block 16 and tail block and pins 18.

Said sound box 10 has the sound openings 15, preferably in the front and rear sides 13 75 and 14 and back 12 rather than through the sound board 11 to thereby increase the resonating power of said sound board. The sound box 10 preferably has the tuning pin block 16 with the pins 17 therein for the attachment of the upper ends of the strings, and the tail block 18, said strings preferably drawing over the cross bar 19 and bridges 20 and 21.

The strings preferably consist of the set of 85 steel guitar strings 22 tuned in unison, which are arranged near the front edge of the sound board 11, being drawn over the bridges 20 and 21 on said sound board 11 between the tuning pins 17 and bar 19 in Fig. 1, and 90 between pins 17 and tail pins 18 in Fig. 6, and having the position marks 27 beneath said guitar strings for playing the same in the usual manner with the playing steel 48.

Other groups of accompaniment strings 23 95 and 24 are provided, which other groups of accompaniment strings are preferably tuned to the chords represented in the different letters as shown in Figs. 1 and 5; the one essential improvement in string arrangement being that the group 23 of accompaniment strings nearest to and alongside said guitar strings 22 are tuned to the same major key as said guitar strings 22 so that the steel 48 used in playing said Hawaiian 100 steel guitar strings 22 may extend over said adjacent accompaniment strings 23 tuned to chord with the open strings 22 and thereby enlarge the volume of the instrument and enable the player to obtain new and pleasing 105 110

effects heretofore unobtainable, the rest of said groups of accompaniment strings 24 being used to obtain the effect of one or more other instruments accompanying the leading 5 instrument, that is, the guitar strings 22 and first accompaniment group 23 which carry the melody.

As stated, it is necessary that said adjacent group 23 of the accompaniment strings 10 must be tuned to the same key as the guitar strings 22; thus in Fig. 1 the guitar strings 22 are tuned to the note of C, whereas in Fig. 5 said guitar strings 22 are tuned to the note of F. In Fig. 1 the group of accompaniment strings 15 are in the chord of C in order to play in harmony with the guitar strings 22 pitched to the note or key of C, and in Fig. 5 the group of accompaniment strings 23 is tuned to the chord of F in 20 order to play in harmony with the guitar strings 22 in the note or key of F.

In Fig. 1 at the rear side of the instrument, the regular arrangement of guitar strings with fretted finger board is provided 25 so that a melody may be carried upon said guitar strings, the frets 26 being provided beneath said guitar strings for playing the same in combination with the guitar strings 22. Instead of the arrangement of guitar 30 strings 25 as shown in Fig. 1, mandolin strings 28 arranged as usual in pairs may be provided as shown in Fig. 5 with the finger board 29 having frets 30 thereon so that a mandolin effect may be obtained by the 35 player in combination with the guitar strings 22 and accompaniment strings 23 and 24.

In order to change the key of the accompaniment strings 23 and 24, one or more 40 angular fret bars 31 and 32 are preferably rotatably mounted in brackets 33 on the sound board 11 near the upper bridge 21, the angular ends 34 of said rotatable fret bars 31 and 32 permitting the quick and accurate actuation of the same, whereby they 45 may be turned against the accompaniment strings 23 and 24 to change the same to different keys as desired in combination with the strings 22. The rotative actuation of 50 said rotatable fret bars 31 and 32 is preferably attained by means of arm pressure as shown in Figs. 5, 6, 7, 8 and 9.

Said arm actuation is attained by means of the arm pressure board 35 and rod 38 55 which is hinged to the board 36 supported above the strings at the lower end of the sound box 10 by means of brackets 37. Said hinged arm pressure board 35 is capable of downward movement and has the rod 38 60 lengthwise above the same so that the arm shall be able to press quickly and positively upon said hinged board 35 in pressing the same downward. Said hinged board 35 is connected to the lower angular ends 34 of 65 the fret bars 31 and 32 by means of a link

39 having the spring 40 thereon and pins 41 to press against said angular ends 34. The opposite end of said link 39 is connected to the actuating hinged arm board 35 by means of the bell crank lever 42 and link 43, all 70 pivotally connected to one another and to said pressure board 35 so that when the arm is pressed upon the rod 38, said board 35 is moved downward in the degree desired. Thus when moved down slightly as shown 75 in Fig. 7, the spring 40 enables the player to turn the fret bar 32 nearest the pin 17 and bar 21 into holding engagement against the accompaniment strings, thereby completely 80 changing the chord or key of said accompaniment strings, but not of the strings 22; and when it is desired to change the key by turning the rotatable bar 31, the arm of the operator or player presses the rest bar 38 still farther downward, thereby actuating 85 both the rotatable fret bars 31 and 32 as shown in Fig. 8. As soon as it is desired to change back to the normal key, the arm pressure is released on the bar 38, and the spring 40 instantly presses said rotatable 90 bars and said actuating mechanism back to normal position.

Said rotatable bars 31 and 32 may be provided with pedal actuation as shown in Fig. 1, but the arm control is far preferable for 95 most instruments, being better under control and applicable to small and large instruments and does not take as much room, being arranged in small space upon the sound box 10 closely adjacent thereto. 100

The sound box 10 is preferably constructed with the sound board 11 having the cross-wise ribs 44 on the under side of the same. In order to leave the sound board 11 free to resonate, it is found preferable to support said sound board by means of a cross-wise bar 45 as shown in Fig. 2. The bar 45 engages upon the side cleats 46 at each end and has a plurality of support blocks 47 between said rib and the bar 45. The ribs 44 105 preferably do not extend out against the edgewise pieces 13, thereby leaving the sound board 11 free to resonate. Said sound board and sound box construction are claimed under another application, Serial No. 424,163, 110 filed Nov. 15, 1920. 115

I claim as new:

1. In a musical instrument, steel guitar strings, accompaniment strings located alongside said strings and tuned to the same 120 key, and a playing steel of sufficient length to cover both sets of strings while playing the same.

2. In a musical instrument, a set of lead or melody strings and sets of accompaniment strings placed side by side, a plurality of rotatable fret bars arranged to bear against said sets of accompaniment strings to change the key of the same, a bar to receive arm pressure, and link and bell crank 125 130

connection between said bar and said rotatable fret bars to actuate the same.

3. In a musical instrument, a set of lead or melody strings, sets of accompaniment strings alongside said set of lead or melody strings to be coöperatingly played therewith, a plurality of rotatable fret bars placed beneath said strings to change the key thereof, said fret bars having angular ends, a pressure bar hinged at the tail of the instrument to receive arm pressure, a bell crank lever connected to said bar, link connection between said bell crank lever and the angular ends of said rotatable fret bars, and pins 10 and a spring on said link to actuate one or more of said angular ends of said fret bars according to the amount of pressure on said bar.

4. In combination with a stringed instrument, a plurality of movable fret bars, a movable member, and means connecting said fret bars to the member whereby upon a certain movement of the member a predetermined one of said bars will be moved to 20 operative position and upon a second movement of said member a second one of said bars will be moved to operative position.

5. In a stringed instrument, a set of

strings, a set of accompaniment strings located adjacent to said first strings so as to 30 be coöperatingly played and a playing steel of sufficient length to cover both sets of strings.

6. In combination with a stringed instrument, a plurality of movable fret bars, a 35 movable member, hinged to the tail end of the instrument and extending thereacross, and connecting means between said fret bars and the member whereby upon predetermined downward movement of the member 40 one of the bars will be moved to operative position, and upon further downward movement of the member the other bar will be moved to operative position.

7. In combination with a stringed musical 45 instrument, an elongated arm-controlled member hinged to and extending across the tail end of the instrument, a movable fret bar, and means to actuate said bar by said member.

In testimony whereof I have affixed my signature in the presence of two witnesses.

EUGENE B. HARRINGTON.
